UNITED STATES PATENT OFFICE

IRVING G. SCOTT AND MAUD C. FOX, OF NEW YORK, N. Y.

DESIGN FOR A FLOWER STAND

Application filed November 24, 1930. Serial No. 37,781. Term of patent 3½ years.

To all whom it may concern:

Be it known that I, IRVING G. Scott, a citizen of the United States, residing at New York city, in the county of New York, State of New York, and I, MAUD C. Fox, a citizen of the United States, residing at New York city, in the county of New York, State of New York, have invented a new, original, and ornamental Design for a Flower Stand, of which the following is a specification, reference being had to the accompanying drawing, forming part thereof.

The figure is a perspective view of a flower stand, showing our new design.

We claim:

The ornamental design for a flower stand as shown.

IRVING G. SCOTT.
MAUD C. FOX.
